UNITED STATES PATENT OFFICE.

HENRY KUCHMANN, OF HOBOKEN, NEW JERSEY.

PHOTOGRAPHIC-PLATE-HOLDER KIT.

Application filed May 24, 1924. Serial No. 715,646.

To all whom it may concern:

Be it known that I, HENRY KUCHMANN, a citizen of the United States, residing at Hoboken, in the county of Hudson and State 5 of New Jersey, have invented certain new and useful Improvements in Photographic-Plate-Holder Kits, of which the following is a specification.

This invention relates to new and useful 10 improvements in photographic plate holder kits for cameras, and has for its principal object to provide a simple and efficient means for holding a photographic plate in the kit, without having to adjust clamping 15 members in order to hold the plate in position in the kit.

A further object of the invention is to provide a device of the above mentioned character, wherein considerable time and 20 labor will be saved in placing the photographic plate and supporting the same in position in the kit and further preventing the accidental displacement of the plate from the kit.

25 A further object of the invention is to provide a device of the above mentioned character, which is simple in construction, inexpensive, strong and durable, and further well adapted for the purposes for which it 30 is designated.

Other objects and advantages will become apparent during the course of the following description.

In the accompanying drawing, forming a 35 part of this specification, and in which like numerals designate like parts throughout the same:

Figure 1 is a front elevation of my improved kit,

40 Figure 2 is a rear elevation thereof,

Figure 3 is an end elevation, and

Figure 4 is a detail perspective view of the frame comprising my improved kit, with one of the end sections removed.

45 In the drawing, wherein for the purpose of illustration is shown the preferred embodiment of my invention, the numeral 1 designates generally the frame comprising the kit and the same includes the spaced side 50 bars 2 and 3 respectively, which are connected together at one end by means of the end bar or section 4. The opposite end portions of the side bars 2 and 3 have the back faces thereof provided with cut-away portions 55 5 and 6 respectively, and the purpose of this construction is to provide a means for re-

movably and adjustably supporting the extensions 7 and 8 respectively, provided on the ends of the opposite end section 9. The front faces of the end sections 4 and 9 respectively are provided with the inwardly extending slips 10 and 11 respectively, and the same extend between the side bars 2 and 3, in a manner as is obvious from the construction shown in Figure 4. The purpose 60 of this construction is to provide a means for permitting the forward movement or displacement of the photographic plate, which is supported in the frame. For the purpose of preventing the rearward movement of the plate, in the frame, the diagonally extending cross strips 12 are fastened to the back faces of the end sections 4 and the side bars 2 and 3, in the manner as more clearly illustrated in Figure 2 of the drawing. The back faces of the opposite ends 65 of the side bars 2 and 3 have fastened thereon the plate 13, by means of the fastening elements 14 and the plates are adapted to extend over the adjacent end portions of the 70 opposite end section 9 and also the inner upper portion of each of the plates is disposed inwardly of the side bars and end section 9 for engagement with the opposite 75 rear portion of the photographic plate supported in the frame.

It is to be understood, however, that the plates 13 are fastened on the back faces of the side bars 2 and 3 in such a manner as to not prevent or interfere with the sliding 80 movement of the end section 9 with respect to the cut-away portions 5 and 6. The slide- 85 able end section 9 is adapted to cooperate in conjunction with the usual spring of the plate holder, and after the plate is put in position in the kit, it will be impossible for the same to fall out therefrom. A kit of 90 the above mentioned character will eliminate the time and labor which is lost in placing the plates in position in the kits 95 now in use, and furthermore the necessity for small catches, for securing the plate in position in the kit is obviated.

The simplicity of my device enables the same to be manufactured at a very low cost, 100 and it may be constructed of any suitable material, so as to render the same strong and durable.

While I have shown the preferred em- 105 bodiment of my invention, it is to be under- 110 stood that various changes in the size, shape and arrangement of parts may be resorted

to, without departing from the spirit of the invention and the scope of the appended claim.

Having thus described my invention,
5 what is claimed is:

A plate holder kit for cameras in the form of a frame comprising a pair of spaced side bars, an end section connecting the side bars at one end thereof, the opposite 10 ends of said side bars having the back portions thereof provided with notches, an additional end section disposed between the

side bars adjacent the notches, lateral projections provided on the ends of the last mentioned end sections for slidable movement in the notches in said side bars, inwardly projecting portions provided on the front faces of both end sections and disposed between said side bars, and strips extending across the corners of the frame, some of said strips being extended across the notches to hold the lateral projections therein.

In testimony whereof I affix my signature.
HENRY KUCHMANN.
